R. TAYLOR

MACHINE FOR COMBING COTTON AND OTHER FIBERS

Filed Feb. 26, 1924

INVENTOR:
ROBERT TAYLOR
BY: Francis C. Boyce
ATTORNEYS

UNITED STATES PATENT OFFICE.

ROBERT TAYLOR, OF OLDHAM, ENGLAND.

MACHINE FOR COMBING COTTON AND OTHER FIBERS.

Application filed February 26, 1924. Serial No. 695,159.

To all whom it may concern:

Be it known that I, ROBERT TAYLOR, a subject of the King of Great Britain, residing at Soho Iron Works, Oldham, in the county 5 of Lancaster, England, have invented new and useful Improvements in Machines for Combing Cotton and Other Fibers, of which the following is a specification.

The invention relates to improvements in 10 or relating to machines for combing cotton and other fibers and has for its object to provide improved means for adjusting the revolving clearer in such manner that the latter may be adjusted to its best working position according to the position of the top 15 comb and leather detaching roller.

In the accompanying drawings—

Figure 1 is a plan of means for adjusting a clearer roller constructed according to the 20 present invention.

Figure 2 is an end elevation thereof and Figure 3 is a plan of part thereof.

Referring to the drawings—1 represents the revolving clearer roller, 2 represents the 25 ratchet wheel thereof, which if desired may be formed integral with the spindle 3 and 4 represents the pawl by which the ratchet wheel 2 is controlled.

5 represents arms or levers having bearings 5^a at one end by which the same are 30 adapted to be mounted or formed upon a shaft and to the free ends of said arms or levers 5 are pivotally connected arms 6 between which the clearer roller 1 is mounted said arms 6 being supported and frictionally 35 maintained in the position shown on cams or eccentrics 7 carried by studs 7^a which are rotatably mounted in said arms or levers 5.

On the studs 7^a being rotated the cams 7 40 which lie and work within bearings 6^a in the arms 6 also rotate and have a cam like or reciprocatory effect upon said arms 6 by which means the position of the clearer roller 1 may be adjusted within the limits of 45 the throw of the cam 7. The studs 7^a are furnished with heads 7^b by means of which they may be easily turned.

The position of the clearer rollers 1 may be fixed by means of set screws 8 which impinge upon the studs 7^a and fix the same with the arms or levers 5.

It will be understood that the details of construction of the device may be modified without departing from the principle of the 55 invention.

What I claim as my invention and desire to secure by Letters Patent is:

1. In a combing machine, the combination 60 of a pair of oppositely positioned arms, a clearer roller carried by said arms, cams mounted for rotation in said arms and means for rotating said cams to adjust the clearer roller.

2. In a combing machine, the combination 65 of two sets of arms, oppositely positioned arms pivotally connected to the free ends of said first mentioned arms, a clearer roller carried by said second mentioned arms, studs 70 rotatably mounted in said first mentioned arms, cams carried by said studs, and means for turning said studs and cams to adjust the clearer roller.

In testimony whereof I have signed my name to this specification.

ROBERT TAYLOR.
